I. J. F. REMARK

RESILIENT TIRE

Filed July 18, 1924

FIG. 1.

FIG. 2

INVENTOR.
ISIDORE J. F. REMARK

BY *A. L. E.*

ATTORNEY.

UNITED STATES PATENT OFFICE.

ISIDORE J. F. REMARK, OF AKRON, OHIO, ASSIGNOR TO THE GENERAL TIRE AND RUBBER COMPANY, OF AKRON, OHIO, A CORPORATION OF OHIO.

DESIGN FOR A RESILIENT TIRE.

Application filed July 18, 1924. Serial No. 10,180. Term of patent 14 years.

To all whom it may concern:

Be it known that I, ISIDORE J. F. REMARK, a citizen of the United States, residing at Akron, in the county of Summit and State of Ohio, have invented a new, original, and ornamental Design for Resilient Tires, of which the following is a specification, reference being had to the accompanying drawings, forming a part thereof.

In the drawings:

Figure 1 is a plan view looking upon a section of a tire showing my new design; Figure 2 is a cross-section on the line 2—2 of Figure 1.

I claim:

The ornamental design for a resilient tire, as shown.

ISIDORE J. F. REMARK.
